MEANS FOR SECURING COVERS TO
CONTAINERSNeil A. Fowler, Oak Park, Ill., assignor to General
Box Company, Chicago, Ill., a corporation of
Delaware

Application January 25, 1932, Serial No. 588,523

5 Claims. (Cl. 217—36)

This invention relates to fastening means for containers, and more particularly to means for fastening covers to containers quickly, easily and without the need of special tools.

5 In the packing for shipment of vegetables, fruit, and other articles, it is of great advantage to pack the same in the field, orchard, or other place of production, and be able to quickly and readily fasten the cover in place without the use of tools, nails, hammer, or the like. Among the 10 objects of the present invention is to provide fastening means for container covers, and the like, possessing these and other advantages.

15 A further object is to provide such fastening means that will permit the easy removal and replacement of the cover for purposes of inspection, and the like, but which at the same time will securely hold the cover in place during handling and shipping. It is to be understood 20 that the cover may be removed and replaced as often as is found necessary or desirable.

Another object is the provision of fastening means that may be fastened to the cover ready for use, or be separate therefrom but instantly available for use as desired.

25 Further to provide cover fastening means that may normally lie flat against the surface of the cover during shipment of the empty containers and covers, and be instantly available for use by bending the fastening means over the edge of the cover and around a binding wire, cleat, or other available portion of the container.

Also to provide a novel method of securing a cover to a container either of the wire-bound type, 30 or not, as desired.

Further objects, advantages and capabilities will later more fully appear.

35 My invention further resides in the combination, construction and arrangement of parts illustrated in the accompanying drawings, and while I have shown therein preferred embodiments I wish it understood that the same are susceptible of modification and change without departing from the spirit of my invention.

40 Referring to the drawings:—

Fig. 1 is a perspective view of a shipping container, the cover of which is fastened to the body of the container by my improved fastening means.

45 Fig. 2 shows the cover of the container in Fig. 1, with the fastening means in the position which they normally occupy prior to fastening of the cover to the container.

50 Fig. 3 is a cross-sectional detail view showing how the fastening elements are secured to the 55 cover.

Fig. 4 is a fragmentary perspective view showing two of the fastening elements of Fig. 2 bent outwardly, and being inserted back of a binding wire just prior to being bent into the final form shown in Fig. 1.

Fig. 5 is a fragmentary perspective view of a corner of a container similar to the container shown in Fig. 1, except that the binding wire is omitted, and the fastening element is bent inwardly and upwardly around the bottom of the upper cleat of one of the side walls.

Fig. 6 is a fragmentary perspective view of one corner of the shipping container and cover, and showing a modified form of fastening means.

Fig. 7 is a fragmentary view of the cover of Fig. 6, showing the position normally occupied by the fastening elements prior to their being bent into the fastening position shown in Fig. 6.

Fig. 8 is a fragmentary detail showing how the fastening elements of Figs. 6 and 7 are secured to the cover.

Fig. 9 is a fragmentary perspective view of a corner of a shipping container and cover showing a modified form of fastening means.

Fig. 10 is a fragmentary perspective view of a cover such as shown in Fig. 9, but showing the fastening elements in the position which they occupy while the covers are being shipped, but prior to fastening the same on to the container.

Fig. 11 is a perspective view of one of the fastening elements shown in Figs. 9 and 10.

Fig. 12 is a fragmentary sectional detail showing how the fastening elements of Figs. 9, 10 and 11 are applied and bent to fasten the cover in position on the container.

The fastening means shown in Figs. 1, 2, 3 and 4 will now be described in detail.

The container indicated generally at 1 is preferably of the wire-bound type, and is equipped with retaining bands such as binding wires indicated at 2, the same being stapled in position as is accomplished in the usual wire-bound blank machines. This container is shown as of the crate type, and provided with a bottom 3, which may or may not, as desired, be of open-work or crate formation. These crates may, if desired, be shipped to the field, orchard, or other place of use in flat knocked-down condition, or otherwise, as desired. When shipped flat they will be bent into rectangular form, and the wires twisted at the corners in a well-known manner. The bottom of the container will then be placed within the lower edges of the side walls either before or after twisting of the wires, as desired.

The crate or container as thus formed will then

be filled with the vegetables, fruit, or other material to be packed and shipped, the crate being preferably slightly more than filled, so that when the cover 4 is forced into and secured in position the central portion, as at 5, will be more or less bulged upwardly. The cover 4 is shown in Fig. 2 in the condition in which it is shipped to the place of use, in which condition the fastening elements 6 (which are preferably of flat metal) normally lie flat against the upper face of the slats of the crate cover. The outer end of fastening elements 6, as shown in Fig. 3, are first stamped to provide one or more barbs, or the like, 7 (there being two of these barbs shown in Fig. 3), which barbs seat themselves in the wood of the slats 8 of the cover, between which slats and the cleats 9 said ends of the fastening elements are positioned. When the slats and cleats are secured together by fastening elements 10, or other means, such as staples, nails, or the like, barbs 7 will be driven into the wood of the slats or strips. The remaining fastening elements 6 are secured to the cover in like manner.

As soon as the crate is filled the fastening elements 6 are bent outwardly over cleat 9, as shown in Fig. 4. The cover will preferably be applied to the container in the position shown in Fig. 4, in which the cover is placed down upon the packed products and pressed downwardly until the ends of the cover are in a position shown in Fig. 4. This cover may be forced into position by hand, or by a press provided therefor. The fastening elements are then bent backwards and the ends pushed downwardly behind the binding wires 2, whereupon the free end of the fastening elements 6 will be bent upwardly, as shown at 11 in Fig. 1. This will securely fasten the ends of the cover in position upon the container, which fastening operation can be accomplished with the fingers of the operator without the use of special tools, nails, hammer, or the like, and the cover may also be readily removed for inspection whenever desired, and replaced as often as found necessary and desirable. This affords a fastening means capable of being quickly and easily applied, and one that will securely hold the cover in position during shipping.

As shown in Fig. 5 the binding wires 2 may be omitted, and the fastening elements 6 bent downwardly along the outer face of the upper cleat 12 of the end wall which functions as the retaining band in this figure, and then bent beneath this cleat 12 and upwardly on the inner side thereof, as shown in dotted lines at 13. It will thus be readily seen that the fastening elements 6 are adapted for use in connection with containers with or without binding wires, as the case may be. It is also understood that while I have shown in Figs. 1 to 4 a container of the crate form, the walls may be solid if preferred. If the walls of the container are solid it is only necessary to push the free ends of fastening elements 6 behind the binding wires, and then bend the same upwardly around the binding wire. Likewise, the fastening elements need not necessarily be attached to a slat or cleat, as the top or cover may be solid or of one piece, or with but a cleat through the center, and the fastening elements may be attached direct to the cover or top.

Fig. 6 shows a modified form of my improved fastening means, in which the fastening elements 14 are formed of wire bent back upon itself intermediate of its length to form a pair of parallel legs, shown in Fig. 7, the free ends 15 of the parallel legs being inserted through the cleats 9 and

strips 8 of the cover, and clinched on the inner face of the cover, as shown at 16 in Fig. 8. In this form the fastening elements are bent inwardly substantially parallel with the upper face of the cover, as shown in Fig. 7, which position they continue to occupy until ready for use. This enables the covers to be shipped separate from the crates or container without danger of unduly bending the fastening elements.

When the container is filled and the cover is ready to be secured thereto it is placed in position on the container, and the fastening wires 14 are bent outwardly over the outer edge of the cleat 9 and downwardly behind the binding wire 2, and then laterally and upwardly as at 17 around the binding wire (see Fig. 6), which completes securing of the cover in position when all of the plurality of fastening elements have been secured, as just described. It is also understood that this type of fastening element may also be used in connection with a container not provided with binding wires, in which event the fastening elements 14 will be bent beneath and upwardly on the inside face of the top cleat of the end wall of the container, in a manner similar to that shown in Fig. 5 in connection with the form of fastening element of Fig. 1.

Another form of fastening element is shown in Figs. 9 to 12, inclusive, in which the fastening element 20 is formed of a single length of flexible wire bent upon itself intermediate of its ends to form two parallel legs, the inner end of each of which leg is bent to form a hook 21. When shipping the covers these hooks 21 are hooked over the outer edge of each end of the cover, as shown in Fig. 10, so that the body of the fastening element will extend inwardly of the cover and parallel therewith, so as to not be unduly bent prior to the fastening of the cover onto the container.

When it is desired to fasten the cover onto the container the fastening elements 21 are moved outwardly to release hooks 21 from the outer edge of the cover, and the hooks are then hooked over the inner edge of cleats 9, after the manner shown in Figs. 9 and 12. This causes the body portion of the fastening elements to extend outwardly over the edge of the cover, and they are then bent downwardly at 22 (see Fig. 12) and passed behind binding wire 2, and then bent laterally and upwardly, so that the free end 23 lies closely adjacent the downwardly extending portion 22. When each of the plurality of fastening elements is bent and thus secured in position the cover will be firmly fastened to the container, but yet removable by a reverse operation of each of the fastening elements to permit inspection of the contents of the container when desired.

The covers of the containers will preferably be made of a slightly greater length than the length of the container, so that when the container is slightly more than filled the cover will be pressed down over the contents and caused to bulge somewhat, especially near the middle portion, which bulging will foreshorten the cover to approximately the same length as the length of the container. This, however, is not indispensable, as the invention is also applicable with covers of the same length as the length of the container, if desired.

Having now described my invention, I claim:

1. In combination a wire-bound container, a cover having cleats at its end edges and flat metal flexible fastening elements secured between the cleats and cover and adapted to extend inwardly of the cover ends and lie flat

- against the cover prior to fastening the cover on the container, said fastening elements, when the cover is being secured to the container, being bent outwardly and downwardly to extend over the edge of the cover and behind the adjacent binding wire, the free end of the fastening element extending upwardly from the binding wire and occupying a position closely adjacent the downwardly extending portion.
2. In combination a wire-bound container, a cover having a cleat at each end, one or more flexible wire fastening elements each having one end secured to a cleat, each of said fastening elements extending inwardly of the ends of the cover to lie approximately parallel therewith prior to its use as a cover fastener, each of said elements when used to fasten the cover to the container being bent upwardly and outwardly to extend over the outer edge of the cleat and then downwardly in close engagement therewith, the downwardly extending portion passing behind an adjacent binding wire and being bent laterally and upwardly in close engagement therewith.
3. In combination a wire-bound container, a cover having a cleat at each end on the upper side thereof, and metal flexible fastening elements secured between said cleats and cover and adapted to extend inwardly of the cover ends and substantially parallel to the cover prior to fastening the cover on the container, said fastening elements when the cover is being secured to the container being bent upwardly, outwardly and downwardly to extend over the edge of the cover and behind the adjacent binding wire, the free end of the fastening element extending upwardly from the binding wire and occupying a position closely adjacent the downwardly extending portion.
4. In combination a container and a cover therefor, side walls for said container, said side walls each having a transversely extending strengthening member at its upper edge, said cover having a cleat at each end on its upper side, a flexible metal fastening element secured to each of said cover cleats to lie approximately horizontal on the cover to extend inwardly from the cover ends prior to being bent into fastening position, said fastening elements when the cover is being secured to the container being bent outwardly and downwardly to extend over the edge of the cover and then underneath and around the lower edge of said transversely extending member.
5. In combination a container and a cover therefor, side walls for said container, said side walls each having a retaining member extending along its upper edge, around which flexible fastening elements may be bent, said cover having cleats at its end edges on the upper side thereof, flexible metal fastening elements secured between the cleats and cover and adapted to extend inwardly of the cover ends and lie flat against the cover prior to fastening the cover on the container, said fastening elements when the cover is being secured to the container being bent outwardly and downwardly to extend over the edge of the cover and then underneath and around the lower edge of said retaining member.
